UNITED STATES PATENT OFFICE.

LOUIS H. AYER, OF CHICAGO, ILLINOIS.

BONDING PIN.

Application filed February 9, 1923. Serial No. 617,969.

My invention relates to bonding pins of the type which are used for connecting electrical conductors to rails.

Tapered bonding pins are commonly employed for connecting electrical conductors to rails, such pins being formed with one or more longitudinal grooves in which the conductor is clamped by wedging engagement of the pin in an aperture of the rail. It is customary to make these tapered pins of circular cross section so that a substantially uniform compressing strain is imposed on the pin as it is driven into the aperture of the rail, and the depth and arrangement of the groove is such that a substantial portion of the conductor is exposed for direct wedging engagement with the aperture of the rail. This construction however, results in a considerable mutilation or peeling back of the conductor which is of comparatively soft material at the edge or corner of the aperture, and not only reduces the conducting capacity but also increases the liability of breakage.

The principal objects of my invention are to minimize the peeling back or mutilation of the side of the conductor when clamped to a rail by means of a bonding pin; to construct the bonding pin so that the compressing strain resulting from the wedging engagement of the pin in the aperture of the rail tends to compress or force and close the sides of the bonding pin over the exposed portion of the conductor to frictionally engage the wire or conductor on all sides or entirely around its circumference to prevent peeling or shearing; to effect a better electrical connection as well as a more substantial mechanical connection; and in general, to provide an improved bonding pin which is simple and inexpensive and capable of being used in place of other bonding pins without requiring any change in the form of the conductor or the formation of the rail aperture.

On the drawings:

Fig. 1 is an enlarged side view of a bonding pin constructed in accordance with my invention;

Fig. 2, a view looking at the smaller end of the bonding pin;

Fig. 3, a view partly in section showing the manner of connecting rails with my bonding pin;

Fig. 4 an enlarged view taken on the line 5—5 of Fig. 3, showing the bonding pin in

place before it is driven into the rail aperture;

Fig. 5, a similar view showing the bonding pin driven into place; and

Fig. 6 an enlarged view showing the rail in section on the line 6—6 of Fig. 3.

Referring to the drawings, the numerals 1—1 indicate two adjoining rails, 2 a conductor for connecting the two rails and 3—3 apertures in the rails in which the ends of the conductor 2 are secured. The bonding pin is indicated as a whole at 4 and is tapered at one end as indicated at 5 to facilitate insertion in the aperture 3 of the rail. A groove 6 extends from end to end of the pin to receive the conductor 2, and the portion 7 of the pin beyond the tapered portion 5 is also tapered, but more gradual than the portion 5, so as to afford a driving fit in the aperture 3, whereby the pin is not only secured in the aperture but also caused to grip the conductor 2 in the groove 6.

The taper of the portion 5 of the pin may be of ordinary conical formation, that is, of such a form that it is circular in cross section, but the portion 7 is of a special tapered form to effect a more substantial clamping or gripping of the conductor 2 in the groove 6 and also to avoid unnecessary mutilation of the wire. To this end the portion 7 is not tapered in the mid plane A—A of the groove 6, but is of a uniform thickness substantially the same or a trifle greater than the diameter of the rail aperture 3 in which it is to be inserted. In other words, assuming that the groove 6 is omitted as indicated by dotted lines in Fig. 2, the tangent planes B—B, C—C at opposite sides of the pin are substantially parallel. The pin is however, tapered in the plane D—D at right angles to the mid plane being formed about divergent axes so that the portion 7 is of gradually increasing elliptical or oval transverse form from the inner end of the taper 5 to the remote end of the pin.

With this construction there is practically no wedge action on the pin in the mid-plane A—A of the groove, but merely a snug fit, and the groove 6 is arranged with the bottom thereof parallel with the planes B—B, C—C so that the conductor 2 fits in the groove with the axes thereof substantially parallel with the planes B—B, C—C, thereby substantially obviating wedge action between the conductor and the wall of the aperture 3. The groove 6 is also of such a depth

that the conductor 2 is seated well in the groove so that only a small portion of the conductor is exposed for engagement with the rail aperture, such engagement being provided to afford a scraping action between the conductor and edge of the rail aperture to clean the surfaces and insure a good electrical connection between the conductor and rail.

10 With the construction described, when the conductor 2 is laid in the groove 6 and the pin driven into the rail aperture 3, the compressing strain of the wedge engagement is applied to the pin at opposite sides of the groove 6 and only a snug fit occurs between the pin and conductor and rail aperture in the mid plane A—A of the groove, thereby affording relief for the compressing strain in circumferential directions at each side of the wedge plane D—D. This results in a slight crowding of the grooved side of the pin against the corresponding side of the aperture 3, sufficient to press the conductor firmly against the rail aperture, and also causes the lips or outer extremities of the side walls of the groove to fold over and compress the top and bottom of the conductor substantially as shown in Fig. 5, so that the conductor is clamped down in the groove 6 and snugly engaged by the pin 4 entirely therearound excepting at the portion of its surface where contact is had between the conductor and rail. A perfect electrical connection is thus afforded as well as a substantial mechanical connection without the excessive mutilation or peeling back and shearing of the conductor as in previous bonding pin structures and the capacity of the conductor is practically unimpaired and liability of breakage or shearing reduced to a minimum.

While I have shown and described my invention in a preferred form, I am aware that various changes and modifications may be made without departing from the principles of my invention, the scope of which is to be determined by the appended claims.

I claim as my invention:

1. An electrical connector comprising a longitudinally grooved body having a tapered end portion, the remaining portion of the body having the same thickness throughout on a plane bisecting the groove, and of gradually increasing thickness on planes at right angles to the plane bisecting the groove.

2. An electrical connector consisting of a longitudinally grooved pin of uniform thickness for a major portion of its length from its head end on a plane bisecting the groove, and of gradually increasing thickness on planes at right angles to the plane bisecting the groove.

3. An electrical connector consisting of a longitudinally grooved pin of substantially

elliptical cross section having an entering portion, the thickness of the pin on a plane bisecting the groove being constant beyond the entering portion, and the thickness of the pin on planes at right angles to the plane bisecting the groove gradually increasing to the end of the pin remote from the entering portion.

4. The combination with a rail having an aperture therein, of a longitudinally grooved pin adapted to be inserted in said aperture, said pin being of gradually increasing thickness on planes at right angles to the plane bisecting the groove so that the maximum compressing strain imposed thereon when inserted in the aperture is at right angles to said plane bisecting the groove.

5. The combination with a rail having a circular aperture of a tapered, longitudinally grooved pin adapted to be inserted in said aperture, said pin being of a form so that the maximum compressing strain imposed thereon when inserted in the aperture of the rail is at right angles to a plane bisecting the groove.

6. A bonding pin having a tapered portion and a longitudinal groove with the bottom thereof parallel to the axis of the pin, said pin being of uniform thickness on a plane bisecting the groove beyond the tapered portion and of gradually increasing thickness on one side of the plane bisecting the groove.

7. An electrical connector consisting of a longitudinally grooved pin having an entrance end and being of uniform thickness on a plane bisecting the groove and extending to the longitudinal axis of the pin, from the entrance end to the head end and of gradually increasing thickness on opposite sides of the plane bisecting the groove.

8. A bonding pin having a tapered entrance end and a longitudinal groove of uniform depth with the bottom thereof parallel to the axis of the pin, the pin being of uniform diameter in a radial plane bisecting the groove and increasing in diameter on one side of the bisecting plane from the tapered entrance end to the remote end of the pin to provide a pin of substantially oval cross-section with portions increasing in radial dimension and eccentricity toward the head end of the pin on one or more sides of the groove.

9. An electrical connector comprising a longitudinally grooved pin adapted to be inserted in a circular aperture of a rail web or the like, the groove of which is adapted to receive a conductor wire, said pin being of such form that the maximum compression strain imposed thereon against the wire when the pin is driven into the aperture with the wire in the groove, is at right angles to the radial plane bisecting the groove.
